UNITED STATES PATENT OFFICE.

EDMUND PYNE, OF NEW YORK, N. Y., ASSIGNOR TO THE BIGELOW CARPET COMPANY, OF CLINTON, MASSACHUSETTS.

DESIGN FOR CARPET.

Specification forming part of Design No. **10,889**, dated October 29, 1878; application filed July 31, 1878.
[Term of patent 3½ years.]

To all whom it may concern:

Be it known that I, EDMUND PYNE, of New York city, county and State of New York, have invented a new and original Design for a Carpet, of which the following is a specification:

This invention relates to a new design for a carpet, oil-cloth, or similar fabric, and the border thereof.

It consists of the new ornamentation of parts hereinafter pointed out.

The accompanying photograph illustrates my new design.

In the photographic illustration, the letter A represents my newly-designed carpet. B is the border thereof.

The carpet A is composed of peculiar groups, a, of flowers, the center of every such group being roses, which are surrounded by star-flowers, forget-me-nots, and fern-leaves, pertaining to the same group.

Large palm-like leaves b b constitute a second and distinct series of groups dividing the groups a. Moss is interspersed between the two groups, giving to the design a peculiar, rich, and natural effect.

The border B also contains the groups a b, but is, in addition thereto, ornamented by two parallel stripes, c d, and by a fancy margin, e. The inner line of the stripe d is undulated, each undulation embracing a rosette-like ornament, as shown.

I claim—

The design for a carpet, substantially as shown.

EDMUND PYNE.
